ICE CUBE CRUSHER

Francis J. Osuch, Detroit, Mich.

Application September 21, 1932, Serial No. 634,205

7 Claims. (CL. 62—1)

The present invention relates to a novel ice cube crusher of a type adapted to be installed in an electrically operated refrigerator to be driven by the motor forming part of the refrigeration unit therein and an attachment operated through the crusher for driving various household devices.

The primary object of the present invention is to devise an ice cube crusher which may be permanently installed in a refrigerator box to be operated by the electrically driven motor which forms part of the refrigeration unit. The present device includes a hinged chute by means of which ice cubes may be conveniently poured into the crusher to be engaged by a rotatable crushing element and a hinged chute which conveys the cracked ice from the crusher to discharge the same into a suitable receptacle. The intake and discharge chutes may be mounted in either a front or side wall of the refrigerator box and when not in use are hinged moved to nest within the wall and thus present a smooth outer wall surface.

Another object of the present invention is to install a shaft in a refrigerator box to be driven through a hand controlled clutch mechanism by an electric motor which forms a part of a conventional refrigeration unit which is mounted within the box, the shaft having an ice crushing element mounted thereon and having one end projecting into an opening in one of the vertical walls of the refrigerator. The end of the shaft which projects into the wall opening is formed to provide a driving connection for the drive shaft in an attachment which may be removably mounted on the wall adjacent the opening, the attachment being designed to provide a variable speed drive for revolving agitators, stirring or beating elements, fruit juice extractors, reamers, and devices for crushing, grinding, mashing, whipping, kneading, chopping, slicing, shredding, polishing, peeling, pitting and instrument sharpening.

With the above and other ends in view the invention consists in matters hereinafter set forth and more particularly pointed out in the appended claims, reference being had to the accompanying drawings, in which

Figure 1 is an isometric perspective view of a refrigerator having the present ice crusher installed therein and illustrating the chutes in the side wall thereof;

Fig. 2 is a fragmentary cross section of the refrigerator, illustrating the refrigeration unit motor and the ice crusher;

Fig. 3 illustrates, in cross section, a different position of the chutes;

Fig. 4 is a fragmentary cross section taken along line 4—4 of Fig. 2;

Fig. 5 is a cross section taken along line 5—5 of Fig. 4;

Fig. 6 is a plan view of the attachment to be driven by the ice cube crusher shaft;

Fig. 7 is a vertical cross section of the attachment;

Fig. 8 is a vertical cross section of the attachment, illustrating a different position of the same;

Fig. 9 is a perspective view illustrating a modified embodiment of the present invention;

Fig. 10 is a fragmentary cross section illustrating the ice crusher chutes in a different position, and

Fig. 11 illustrates a modified drive for the attachment.

Like characters of reference are employed throughout to designate corresponding parts.

The numeral 1 designates a refrigerator box having the usual food compartments and a compartment in which an electric motor 2 and refrigerating unit 3 are mounted. The compartment in which the motor and refrigerating unit are mounted is illustrated as being located in the lowermost portion of the refrigerator but it is to be understood that the present device is equally adaptable to refrigerators where the motor compartment is located in the top or uppermost portion of the refrigerator.

In the motor compartment of the refrigerator 1 is installed a rotatable shaft 4, one end of the shaft being provided with an opening 5 which is shaped to receive a projection on a shaft presently to be described to provide a driving connection therebetween. The end 5 of the shaft 4 is mounted to project into an opening 6 in one of the side walls of the refrigerator 1. A sprocket 7 is mounted on the shaft of the motor 2 and is connected by a chain 8 to a sprocket 9 that is mounted on the shaft 4 to freely rotate thereon abutting a flange 10 on the shaft. A slidable clutch element 11 is keyed to the shaft 4 to slide thereon and is connected to a hand operated lever 12 by a stirrup 13 so that the same may be manually moved into or out of engagement with a clutch face 14 that is formed on the sprocket 9. When the clutch element 11 is moved into contact with the clutch face 14 on the sprocket 9 a driving connection is established between the motor 2 and the shaft 4.

The shaft 4 extends through the walls 15 that

form the ice crusher compartment and inside the compartment thus formed is provided an ice crushing element 16 that is mounted on the shaft 4 to rotate therewith. In the wall of the refrigerator 5 at a point higher than the crushing element 16 is hingedly mounted a chute 17 into which ice cubes may be poured to enter the crusher compartment. At a point lower than the crushing element 16 a chute 18 is hingedly mounted in the 10 side wall of the refrigerator 1 out of which cracked ice pours after passing the crushing element.

Figs. 2 and 3 illustrate respectively the position of the chutes when the crusher is operating and the position of the chutes when the crusher 15 is inoperative and illustrates the fact that the chutes do not project outwardly when not in use to provide an obstruction that could catch clothing of persons passing the same or interfere 20 with brooms, vacuum cleaners or similar house cleaning implements.

The attachment that is to be driven by the shaft 4 in order to operate various household implements comprises a hollow casing 20 having a flange 21 surrounding its open end, the flange 25 having suitably drilled holes through which screws 22 are passed to enter the screwthreaded holes 23 in the side wall of the refrigerator. The holes 23 and the holes in the flange 21 are so arranged 30 that the casing 20 may be installed in different positions as will be observed by comparison of Figs. 7 and 8.

Mounted in a bearing 24 within the casing 20 is a rotatable shaft 25 having a projecting end 26 shaped to be received in the specially shaped 35 opening 5 in the end of the shaft 4 to provide a driving connection between the shaft 4 and shaft 25. On the inner end of the shaft 25 is mounted a flat faced disk 27. Supported in the casing 20 with its axis at right angles to the axis of the shaft 25 is a shaft 28. One end of the shaft 28 40 projects through the side wall of the casing 20 as at 29 to facilitate the connection of a stirring device or beater 30 or a fruit juice extractor or reamer 31. Slidably keyed on the shaft 28 is a disk 32 which contacts with the disk 27 in a manner 45 whereby rotary movement of the shaft 4 is transmitted through the disks 27 and 32 to the shaft 28.

In order to provide for different speeds of the shafts 25 and 28 relative to each other there is 50 provided a fork member 33 that is received on a screw 34 in a manner whereby rotation of the screw causes movement of the fork in a direction parallel to the axis of the screw. The fork member 33 engages the disk 32 so that movement of the fork by the screw causes the disk 32 55 to move so that it engages the disk 27 at a point nearer or farther away from its axis of rotation and thus decrease or increase the number of revolutions of the disk 32 per revolution of the disk 27. To operate the screw to vary the speed of the disk 32 there is provided a finger piece 35 that is connected to a gear 36 that meshes with a gear 37 mounted on the end of the screw.

In order to crush ice cubes the shaft 4 is caused 60 to rotate to operate the crushing element 16 by moving the hand lever 12 so that the clutch element 11 engages the clutch face 14 on the sprocket 9. The chutes 17 and 18 are then moved to the open position illustrated in Fig. 3 and 65 ice cubes fed into the crusher through the chute 17, the cracked ice being discharged through the chute 18.

When it is desired to use the attachment the 70 casing 20 is secured to the side wall of the re-

frigerator 1 by the screws 22, the position of the casing being determined by the requirements of the device to be operated thereby. When the casing 20 is secured in place by the bolts 22 a driving connection is established between the shaft 4 and shaft 25 by the projection 26 of the latter entering the opening 5 in the former. Movement of the parts is then governed by the hand lever 12 which as above described controls the movement of the shaft 4. The speed at which the different devices 10 (30 and 31) are to be operated varies and the required speed changes are obtained by manipulating the finger piece 35 to rotate the screw 34 and move the disk 32 so that it contacts with the disk 27 at a point nearer or farther away from its 15 axis of rotation.

In Fig. 9 there is illustrated a refrigerator box 1' having a drawer 40 arranged at the top thereof to receive the various implements that are to be operated by the drive mechanism enclosed in the casing 20. In this embodiment the chutes are illustrated as being shown installed in the front wall of the refrigerator box as above described. The construction and arrangement is shown in detail in Fig. 10 which illustrates a chute 17' opening into the crusher compartment 15' at a point above the crusher element 16' and a discharge chute 18' arranged to direct the crushed ice from the compartment 15' after it passes the crushing element. A shaft 4' is employed to rotate the crushing element 16' and is driven by the motor that operates the refrigeration unit through a sprocket 9' through the slideable clutch element 11' which engages a clutch face 14' on the sprocket 9'. A lever 12' is connected by a fork 13' to the slideable clutch element 11' and the lever 12' is in turn operated by a rod 41 which extends through the front wall of the refrigerator box.

In Fig. 11 there is shown an elevated drive for 40 the attachment which comprises a stub shaft 43 mounted within the refrigerator box at a height considerably above the shaft 4'. The stub shaft is recessed in its end to receive the drive portion on the shaft 25 in the casing 20 and in order to 45 drive the stub shaft 43 there is mounted a sprocket 44 on said shaft which is driven by a chain 45 and sprocket on the shaft 4' which is operated through the clutch mechanism above described. In this manner provision is made for mounting 50 the attachment casing 20 at a height whereby it may be conveniently operated.

Although a specific embodiment of the present invention has been illustrated and described it is to be understood that various changes may be 55 made in the details of construction without departing from the spirit of the invention as set forth in the following claims, and such changes are contemplated.

What I claim is:

1. In a refrigeration cabinet adapted to be cooled by a mechanically operated unit, the combination of a motor adapted to operate said unit, means for receiving and operating interchangeable household devices, a driving element in said cabinet, means operatively connecting said driving element with said motor, and means for mounting said first named means on said cabinet in coupled relation with said driving element.

2. In a refrigeration cabinet adapted to be 70 cooled by a mechanically operated unit, the combination of a motor adapted to operate said unit, a driving element in said cabinet having a coupling device thereon externally exposed through an opening in said cabinet, means operatively 75

connecting said driving element with said motor, means for receiving and operating interchangeable household devices, an externally exposed coupling device on said second named means, 5 and means for mounting said second named means on said cabinet with said coupling devices in coupled relation.

3. In a refrigeration cabinet adapted to be cooled by a mechanically operated unit, the combination of a motor adapted to operate said unit, 10 means for receiving and operating interchangeable household devices, a driving element in said cabinet, means manipulable from outside of said cabinet for operatively connecting said driving element with said motor, and means for mounting said first named means on said cabinet in coupled relation with said driving element.

4. In a refrigeration cabinet adapted to be cooled by a mechanically operated unit, the combination of a motor adapted to operate said unit, a driving element in said cabinet having a coupling device thereon externally exposed through an opening in said cabinet, means operatively connecting said driving element with 25 said motor, a manual control for said means externally exposed through an opening in said cabinet, means for receiving and operating interchangeable household devices, an externally exposed coupling device on said means, and means 30 for mounting said second named means on said cabinet with said coupling devices in coupled relation.

5. A mechanical refrigerator comprising a cabinet having a food compartment, a refrigerator motor compartment, and an ice cube crusher compartment, all three compartments being relatively sealed and isolated and all three compartments having their own individual doors by means of which access thereto from outside of the refrigerator may be attained individually, a motor in said motor compartment, an ice cube crusher in said crusher compartment, and means manipulable from outside of the refrigerator for operatively connecting the crusher to the refrigerator motor.

6. A mechanical refrigerator comprising a cabinet having a food compartment, a refrigerator motor compartment, and an ice cube crusher compartment, all three compartments being relatively sealed and isolated and all three compartments having their own individual doors by means of which access thereto from outside of the refrigerator may be attained individually, a motor in said motor compartment, an ice cube crusher in said crusher compartment, and means manipulable from outside of the refrigerator for operatively connecting the crusher to the refrigerator motor.

6. A mechanical refrigerator comprising a cabinet having a food compartment, a refrigerator motor compartment, and an ice cube crusher compartment, all three compartments being relatively sealed and isolated and all three compartments having their own individual doors by means of which access thereto from outside of the refrigerator may be attained individually, a motor in said motor compartment, an ice cube crusher in said crusher compartment, and means manipulable from outside of the refrigerator for operatively connecting the crusher to the refrigerator motor, the means being disposed within the refrigerator cabinet except for the handle part thereof which is externally exposed.

7. A mechanical refrigerator having a motor compartment provided with a door, an ice cube crusher compartment provided with a door, an ice cube crusher therewithin and including a rotatably mounted shaft, a motor in said motor compartment, means within the refrigerator for creating an operative connection between the crusher shaft and the motor whereby the crusher shaft may be driven by the motor, and means accessible externally of the refrigerator for manipulating the first mentioned means to create such operative connection.

FRANCIS J. OSUCH.
